INSTRUMENT FOR INDICATING A LIQUID
LEVEL AND THE TEMPERATURE OF THE
LIQUID

Paul H. McDaniel, deceased, late of Fort Wayne, Ind., by
Virginia K. McDaniel, executrix, 1706 Mayflower Road,
Fort Wayne, Ind. 46807

Filed May 6, 1966, Ser. No. 2,208

Term of patent 14 years

(Cl. D52—6)

FIG. 1

FIG. 2

FIGURE 1 is a front perspective view of an instrument for indicating a liquid level and the temperature of the liquid; and

FIGURE 2 is a rear perspective view thereof.

I claim:

The ornamental design for an instrument for indicating a liquid level and the temperature of the liquid, substantially as shown and described.
